UNITED STATES PATENT OFFICE.

GEORGE GODDU, OF WINCHESTER, MASSACHUSETTS, ASSIGNOR TO THE UNITED SHOE MACHINERY COMPANY, OF NEW JERSEY.

MACHINE FOR FORMING SCREW-THREADED WIRE.

SPECIFICATION forming part of Letters Patent No. 655,223, dated August 7, 1900.

Application filed August 17, 1898. Serial No. 688,770. (No model.)

To all whom it may concern:

Be it known that I, GEORGE GODDU, a citizen of the United States, residing in Winchester, in the county of Middlesex and State of Massachusetts, have invented an Improvement in Machines for Forming Screw-Threaded Wire, of which the following description, in connection with the accompanying drawings, is a specification, like letters and numerals on the drawings representing like parts.

This invention relates to a machine for forming screw-threads on wire or like cylindrical bodies, and is especially designed and adapted for forming screw-threaded wire having a substantially-large number of threads to the inch and such as is used in the manufacture of boots and shoes.

My present invention has for its object to provide a simple and efficient machine which is particularly well adapted for accurately forming a substantially large number of substantially deep screw-threads to the inch or other predetermined length without hardening or otherwise injuriously affecting the wire, so as to render the finished wire brittle and liable to break under torsional strain to which it is subjected when turned or inserted into the work, such as the outer sole of a boot or shoe.

In accordance with this invention the injurious action to the wire above referred to may be avoided with a machine in which the wire is presented to the threading-rolls in its normal condition and is yet held in front of the threading disks or rolls from twisting in such manner as will not subject it to a hardening or other injurious action. This result may be accomplished in accordance with this invention by providing a machine in which the wire on its passage to the threading rolls or disks is caused to move in a path at an angle with and preferably approximating a right angle to the path of movement of the wire while under the action of the threading disks or rolls, which in the present case are loosely mounted and are carried about the wire and act as feed-rolls. The threading-disks may and preferably will be of a special construction, as will be described. These and other features of this invention

will be pointed out in the claims at the end of this specification.

Figure 1 is a plan view of a machine embodying this invention; Fig. 2, an elevation of the machine shown in Fig. 1 looking in the direction of the arrow thereon; Fig. 3, an elevation of the machine shown in Fig. 1 looking toward the left; Fig. 4, a sectional detail taken on the line 4-4, Fig. 3, looking toward the right; Fig. 5, a longitudinal horizontal sectional detail, on an enlarged scale, to be referred to; Fig. 6, a sectional detail on the line 6-6, Fig. 5; Figs. 7 and 8, details to be referred to.

The operating parts of the machine herein shown as embodying this invention are supported upon a suitable base or table A, provided with suitable legs A'. The base A, as shown, has erected from it an upright A², which supports at its upper end a hollow spindle or stationary shaft a, firmly secured at one end in a suitable opening in the said upright by a clamping-screw a'. (See Figs. 1 and 3.) The hollow spindle or shaft a has loosely mounted upon it a revolvable carrier for threading disks or rolls a² a³, preferably of a construction as will be described, the said carrier being preferably made as herein shown and comprising an outer cylinder or sleeve a⁴, an inner sleeve or cylinder a⁵, separated from the outer cylinder to form an oil well or chamber a⁶, having suitable outlet-ports 20, but which inner cylinder is secured to said outer cylinder. In the present instance the sleeve a⁵ is secured to the cylinder a⁴ by screw-threads a⁷, and the said carrier is secured on the shaft a against endwise movement by a ring a⁸, engaging a flange a⁹ on the said sleeve, a washer a¹⁰, of leather or other like material, being interposed, as shown in Fig. 5. The ring a⁸ is secured to the upright A², as by screws a¹². The cylinder a⁴ is smooth for the greater portion of its length and is adapted to be driven by a belt passed about the same, said belt not being herein shown.

The cylinder a⁴ may be provided at one end, as shown, with an enlarged head or thick annular flange a¹³, provided with inclined faces 23, (see Fig. 3,) which converge toward the 100

axial center of the cylinder, and the said head is provided with a diametrical slot or opening a^{14} , (see Figs. 3 and 5,) in which are dovetailed or otherwise fitted sliding blocks $a^{15} a^{16}$, 5 provided with inclined faces corresponding in pitch to the faces 2 3. The sliding blocks $a^{15} a^{16}$ have secured to them, as by screws $a^{19} a^{19}$, studs or pins $a^{20} a^{21}$, upon which are loosely mounted the threading disks or rolls $a^2 a^3$, the 10 said disks being preferably provided, as shown, with antifriction or roller bearings $a^{24} a^{25}$. The threading-disks $a^2 a^3$ may further be provided with ball-bearings $a^{26} a^{27}$ on their opposite sides or faces, (see Fig. 3,) the balls 15 a^{26} being located in an annular groove in a disk or plate a^{29} , secured to each sliding block $a^{15} a^{16}$, as by screw a^{30} , and the balls a^{27} are located in an annular groove in the front face of each threading-disk $a^2 a^3$ and retained 20 therein by heads a^{31} on the pins or studs $a^{20} a^{21}$. The sliding blocks $a^{15} a^{16}$ are adjustable in the dovetail slot a^{14} , preferably, as herein shown, by means of a shaft or rod a^{32} , provided with right and left threads or worms 25 $a^{33} a^{34}$, (see Fig. 4,) which engage corresponding threads on the sliding blocks $a^{15} a^{16}$. By turning the shaft or rod a^{32} the threading-disks may be moved toward or from each other, according to the diameter of the wire 30 to be threaded.

By reference to Figs. 3 and 5 it will be seen that the threading-rolls are loosely mounted on their studs or pins $a^{20} a^{21}$ and are free to rotate thereon, while at the same time they 35 are revolved or carried about the wire b to be threaded by the rotation of the cylinder a^4 about the shaft a . It will further be noticed from Fig. 3 that the threading-disks are set at an angle to each other, which angle may 40 be changed, according to the pitch of the thread desired to be formed on the wire. The rotation of the carrier a^4 for the threading-rolls, combined with the angular position of said rolls, effects the feed of the wire in the 45 proper or desired manner and at the desired rate to form on the wire a uniform and predetermined number of threads to the inch or other length. The rotation of the carrier for the threading-rolls may be effected by a driving-belt passed about the cylinder a^4 , as above 50 described, or in any other suitable or desired manner.

The wire b under the action of the threading rolls or disks carried about the same by 55 the rotation of their carrier is subjected to a considerable torsional strain, and the primary feature of this invention consists in resisting the aforesaid torsional strain, so as to prevent twisting or turning of the wire without 60 hardening or otherwise injuriously affecting the wire—that is, without subjecting said wire to such pressure or gripping force as will crush, harden, and render brittle the wire. This desirable result I accomplish by 65 causing the wire on its passage to the threading-rolls to move in a path at an angle with

and preferably approximating a right angle to the movement of the wire while under the action of the threading rolls or disks. In the present instance I have shown one form of 70 mechanism which I prefer, with which the angular direction of the wire may be effected. The mechanism herein shown consists of a grooved wheel or roll b' , loosely mounted on a stud b^2 , and a second grooved wheel or roll 75 b^3 , loose on a stud b^4 and preferably provided with a groove of a depth equal to or greater than the diameter of the wire b . The roll b^3 may and preferably will be adjustable toward and from the roll b' to insure proper 80 bending of the wire. The rolls $b' b^3$ are preferably located substantially in line with each other and substantially parallel to the path of movement of the wire while under the action of the threading disks or rolls, and the 85 wire b is passed between the rolls $b' b^3$, (see Fig. 1,) and is thereby caused to move toward the threading-rolls at an angle to the path of movement of the wire while under the action of the said threading-rolls. 90

The wire b may be taken from a reel b^5 , loosely supported on an arm b^6 , secured to the base A and extended substantially at right angles to the carrier for the threading-disks, and the said wire on its passage to the 95 deflecting or bending rolls $b' b^3$ may and preferably will be supplied with oil by means of a wick b^7 , of felt or other suitable material, extended down into an oil pot or vessel b^{10} , supported by a bracket or upright b^{12} , the 100 said wick being secured to a preferably curved flange b^{13} , erected from the top of the oil-pot. The studs $b^2 b^4$, upon which the deflecting or bending rolls are loosely mounted, are fastened to a support, shown as a plate b^{15} , 105 extended from the oil-pot b^{10} , the said plate also having secured to it a block b^{16} , provided with a passage for the wire and forming a guide for the wire. The plate b^{15} may and preferably will have attached to its upper surface, at the rear of the rolls $b' b^3$, a slotted block b^{17} , also constituting a guide for the wire and normally covered by a movable piece or arm b^{18} , which is shown as pivoted at b^{19} to the plate b^{15} and adapted to be turned on its pivot, so 110 as to uncover the slot in the said guide-block. The guide-block b^{18} is extended to near the threading disks or rolls $a^2 a^3$ and firmly supports the unthreaded wire close up to the active surfaces of said disks and presents the 115 said wire in an accurately-central position between the threading-rolls, while a nosepiece b^{20} on the stationary shaft a supports the threaded wire close up to the active surfaces of the threading-disks. The unthreaded wire 120 is drawn from the reel b^5 by the threading-disks, which have the double function of threading and feeding the wire, and is embedded in the wick or oiler b^7 , which acts to keep the wire thoroughly lubricated and facilitates the action of the threading-disks. 125 The oil pot or vessel b^{10} may, if desired, have 130

secured to it a wire-guide b^{22} , normally covered by a plate b^{23} , pivoted at b^{24} . The threaded wire issues from the hollow stationary shaft a through a nose b^{26} and may and 5 preferably will be wound into a coil upon a reel b^{27} , which is, as herein shown, both rotated and reciprocated from the cylinder a^4 , which in the machine herein shown as embodying this invention constitutes the main 10 or driving shaft for the winding mechanism.

The rotation of the reel b^{27} may be effected, as shown, by means of a gear or pinion c , attached to or formed on the cylinder a^4 and meshing with a gear c' , fast on a shaft c^2 , 15 having bearings in the upright A^2 and in a hub c^3 on an arm c^4 , projecting from said upright. (See Fig. 3.) The shaft c^2 has fast on it a worm c^5 , which meshes with and rotates a worm-gear c^6 on a sleeve c^7 , extended 20 through a hub c^8 , attached to the frame of the machine, the said sleeve being secured in said hub against longitudinal movement by a metal washer 50, screwed upon the end of the sleeve c^7 . The sleeve c^7 has extended 25 through it a sleeve c^{12} , provided with a flange c^{10} and having secured to its end beyond the sleeve c^7 a detachable worm c^9 , preferably screwed on the sleeve c^{12} and locked thereon by a suitable check-nut c^{13} . The sleeve c^{12} 30 is engaged with the sleeve c^7 , so as to rotate therewith and yet enable the said sleeve to slip by means of a friction device, preferably leather or like washers c^{14} c^{15} , interposed, respectively, between the flange c^{10} and the sleeve c^7 and between the latter and the worm c^9 . The sleeve c^{12} has extended through it a 35 shaft c^{17} , on which the reel b^{27} is fastened, and the said shaft is engaged with the sleeve c^{12} , as shown by a pin or stud c^{18} , fast on the flange c^{10} , extended into a suitable hole in the reel b^{27} , and the said pin is made of sufficient length to permit the shaft c^{17} and its reel to be reciprocated without disengaging said shaft from the sleeve c^{12} . The reciprocation of the shaft c^{17} and its attached reel 40 is effected, as shown, by means of an elbow-lever c^{20} , pivoted to the frame of the machine and having one arm c^{21} , provided with a gear-segment c^{22} , in mesh with gear-teeth on a collar or sleeve c^{23} , loose on the shaft c^{17} , but retained thereon against longitudinal movement, as by a shoulder c^{24} and a nut c^{25} . The other arm c^{26} of the elbow-lever engages a cam-groove c^{27} in a hub c^{28} on a shaft c^{29} , supported 50 in a suitable bearing c^{30} and provided with a worm-gear c^{31} , which meshes with and is driven by the worm c^9 .

By reference to Fig. 1 it will be seen that the unthreaded wire b is deflected or bent on 60 its passage to the threading disks or rolls and that the movement of the said wire toward the said threading-disks is thus at an angle to the path of movement of the wire while under the action of the said threading-disks, and 65 by reason of this arrangement the wire is held from twisting or turning by the threading-

disks, which are positively carried about the said wire to feed it along, and in this manner screw-threaded wire may be formed with a substantially-large number of substantially-deep threads to the inch (see Fig. 8) without injuriously affecting the strength and life of the wire, for it will be seen that the outer surface of the unthreaded wire is not crushed or hardened, but is left unbroken and in its 75 original condition, and in this condition it is presented to the threading-disks, and, furthermore, it will be seen that the wire is fed forward by the threading-disks and is not subjected to severe longitudinal and torsional 80 strain and pressure after it is threaded.

The threading-disks may and preferably will be made of substantially-large diameter to avoid heating of the same, and thereby enable the said disks to be run at a great speed 85 and consequently increase the output of the machine.

The active surfaces or peripheries of the threading-disks may and preferably will be made substantially narrow and provided 90 with a plurality of annular projections and grooves, and one of said disks may be provided with one more annular projections than the other, which latter is left with the remainder of its periphery smooth, so as to form 95 a solid support or bearing for the wire while it is being acted upon by the initial projection on the other disk. In the present instance the threading-disk a^2 is shown as provided with four annular projections 3 and the 100 disk a^3 with three annular projections 3 and a smooth portion 4. The annular projections 3 are and may be of the full depth it is desired the thread should have.

With the machine herein shown I am enabled to produce a superior screw-threaded wire having a substantially-large number of substantially-deep threads to the inch from a cheaper wire at a minimum cost without decreasing the ductility of the wire and without varying the number of threads to the 110 inch.

I have herein shown one form of device or mechanism with which the unthreaded wire is caused to move toward the threading disks 115 or rolls in a path at an angle to the path of movement of the wire while under the action of the said threading rolls or disks, whereby the said wire is held from twisting or turning and whereby it may be presented to the action of the threading disks or rolls in its normal condition and without its outer skin or surface being broken, crushed, hardened, or otherwise injuriously affected; but I do not desire to limit my invention to the particular 120 construction of wire deflecting or bending device or apparatus shown.

By reference to Fig. 5 it will be seen that the threading disks or rolls are loose on their studs or pins a^{20} a^{21} and are provided with 125 antifriction center and side bearings, which enables the disks to turn very easily and there-

by in this respect also relieves the wire from torsional strain.

While the mechanism for threading the wire is herein shown as rotatable rolls or disks, the invention should not be limited to this or any other specific mechanism, as I consider that any mechanism for threading wire in the combination with means for bending the wire would be within my invention.

10 I claim—

1. In a machine of the class described, the combination of the following instrumentalities, viz: threading disks or rolls to act on the wire and form the threads thereon, a rotatable carrier for said threading disks or rolls, and means to cause the wire on its passage to the threading-rolls to move in a path at an angle to the path in which the wire is moved while under the action of the said threading-rolls, substantially as described.

2. In a machine of the class described, the combination of the following instrumentalities, viz: rotatable threading disks or rolls to act on the wire and form the threads thereon, and a wire deflecting or bending device to act on the unthreaded wire and cause the same on its movement toward the threading disks or rolls to travel in a path at an angle to the path in which the said wire is moved while under the action of the threading rolls or disks, whereby the said wire is held from twisting under the action of the threading rolls or disks and may be presented to the action of said rolls or disks in its normal condition, substantially as described.

3. In a machine of the class described, the combination with a threading disk or roll of substantially-large diameter having a substantially-narrow periphery provided with a plurality of annular projections and with a smooth portion forming a bearing for the unthreaded wire, of a coöperating threading disk or roll of substantially-large diameter having a substantially-narrow periphery provided with a plurality of annular projections in excess of the annular projections on the first-mentioned disk or roll, one of the annular projections on the second-mentioned roll coöperating with the smooth portion of the other roll, substantially as described.

4. In a machine of the class described, the combination of the following instrumentalities, viz: threading disks or rolls, a carrier for said disks or rolls comprising an outer cylinder or sleeve, an inner cylinder or sleeve secured to the outer cylinder but separated therefrom to form an oil well or chamber, and a head attached to said outer cylinder and having converging surfaces provided with a transverse slot; sliding blocks in said slot provided with oppositely-inclined faces corresponding to the converging surfaces of said head; studs or pins secured to the inclined surfaces of said sliding blocks and upon which said threading-disks are mounted; and anti-friction-bearings for said disks, substantially as described.

5. In a machine of the class described, the combination of the following instrumentalities, viz: threading rolls or disks to act on the wire and form the threads thereon, a rotatable carrier for said threading rolls or disks, a reel for the unthreaded wire, and a deflecting or bending device interposed between said reel and said threading rolls or disks, substantially as and for the purpose specified.

6. In a machine of the class described, the combination of the following instrumentalities, viz: threading rolls or disks to act on the wire and form the threads thereon, a rotatable carrier for said threading rolls or disks, a reel for the unthreaded wire, a deflecting or bending device interposed between said reel and threading rolls or disks; and an oiler for the unthreaded wire interposed between said deflecting device and said reel, substantially as described.

7. In a machine of the class described, the combination of the following instrumentalities, viz: threading rolls or disks to act on the wire and form the threads thereon, a rotatable carrier for said threading-rolls, and means to deflect or bend the wire on its passage to the threading-rolls, comprising loosely-mounted wheels or rolls arranged substantially in line with each other, substantially as described.

8. In a machine of the class described, the combination of the following instrumentalities, viz: rotatable threading disks or rolls to act on the wire and form the threads thereon, a wire deflecting or bending device to act on the unthreaded wire and cause the same on its movement toward the threading disks or rolls to travel in a path at an angle to the path in which the said wire is moved while under the action of the threading rolls or disks, and an oiling device for the unthreaded wire with which said wire makes contact previous to its meeting the deflecting or bending device, substantially as described.

9. In a machine of the class described, threading disks or rolls, supports for said rolls provided with oppositely-inclined faces, disks secured to said oppositely - inclined faces, studs or pins projecting beyond said disks and on which said rolls are loosely mounted, a cap or head on said studs or pins, and antifriction-bearings for the said threading-rolls interposed between said studs and said threading-rolls, and between the threading-rolls and the disks secured to the inclined faces, and between the cap or head on the studs or pins and said threading-rolls, substantially as described.

10. In a machine of the class described, the combination of the following instrumentalities, viz: mechanism to act on wire and form threads thereon, and means to cause the wire on its passage to the threading mechanism to move in a path at an angle to the path in which the wire is moved while under the action of the threading mechanism, substantially as described.

11. In a machine of the class described, the combination of the following instrumentalities, viz: mechanism to act on the wire and form threads thereon, and means to bend the
5 wire before its presentation to the threading mechanism.

In testimony whereof I have signed my

name to this specification in the presence of two subscribing witnesses.

GEORGE GODDU.
